UNITED STATES PATENT OFFICE.

AMMI M. GEORGE, OF NASHUA, NEW HAMPSHIRE.

MACHINE FOR MAKING CHAIN-LINKS.

Specification of Letters Patent No. 12,439, dated February 27, 1855.

To all whom it may concern:

Be it known that I, AMMI M. GEORGE, of Nashua, in the county of Hillsboro and State of New Hampshire, have invented a new and useful Machine for Forming Chain-Links.

The nature of this machine consists in the employment of an inclined knife which cuts the material at a proper bevel for welding, also of a reciprocating former around which the link is formed by means of a pair of rotating dies.

I do hereby declare that the following is a clear and exact description of the construction and operation of the same, reference being had to the annexed drawings making a part of this specification in which—

Figure 1 represents a side elevation. Fig. 2, a birds-eye view or plan; Fig. 3, a longitudinal section; Fig. 4, an end elevation; Fig. 5, a transverse section; Fig. 6, an isometrical perspective; Fig. 7, a detail showing the forming dies and former as they appear with the link just formed.

The whole combination is attached to, and worked upon the bed plate A, the arbor B is the point at which the power is applied, upon which is the beveled tooth wheel D, in gear with the larger beveled tooth wheel C to which is attached the connection rod E at sufficient distance from its center to give it the required reciprocating motion; this connection rod is attached to the sliding plate F to which is confined the arm G, having the former I made fast to it by the bolt K, all receiving the same reciprocating motion; this also gives motion to the knife or cutter J, by means of an oblong slot, working on the end of the bolt K which projects through the arm G sufficiently for that purpose. The other end of the cutter J, is movable on the arbor W which is attached

to the movable plate V held in its place by the set screws X X'.

L represents another part of the cutting apparatus operating in connection with the cutter J.

H represents a lever attached to the arm G by the bolt a upon which it is movable; therefore the sliding plate F in moving backward or outward carries the outer end up the inclined plane Q forcing the inner end down, thereby throwing the link from the former I.

N N' represents a pair of rotating dies working on the arbors P P' on which are the two toothed wheels O O' in gear thereby giving similar motion to the forming dies, which are operated by the moving former I, and upon the retreat of the former they are turned to their original position by the spiral spring b.

M represents a movable gage held in its place by the set screws c the object of having this and the plate v movable is so that the required quantities of material can be taken for different sized links.

U U' are rests upon which the material rests until taken by the former I.

I do not claim as my invention the rotating dies in combination with the reciprocating former; neither do I claim the manner herein described of cutting off the material at the proper bevel for welding; but

What I do claim and wish to secure by Letters Patent is:—

I claim the arrangement of the forked lever H, confined to the arm G in relation to the inclined plane Q and former I, and operated for relieving the former of the link as herein set forth.

A. M. GEORGE.
